SERGE DANILOFF, OF LOWELL, MASSACHUSETTS, ASSIGNOR TO SACO-Lowell SHOPS,
OF BOSTON, MASSACHUSETTS, A CORPORATION OF MASSACHUSETTS.

CAP-TWISTING MACHINE.

Application filed February 3, 1923. Serial No. 616,828.

This invention relates to mechanisms of the character used in the textile industry to twist together several strands or "ends" of thread to form a larger thread or cord of the required diameter. The invention is especially concerned with twisting mechanisms of the cap type.

Cap twisters have been used for a great many years but their commercial use has been confined to worsted thread or yarn. Notwithstanding the fact that this is one of the oldest types of twisting mechanisms, it has never, so far as I have been able to learn, been considered feasible to twist cotton yarn or thread with such a mechanism, the ring type of twister being universally used for cotton yarn and thread. The chief disadvantage of the ring type of twister is that its speed is limited. About 2500 revolutions per minute is regarded as the maximum speed at which it is feasible to run a heavy duty ring twister on ordinary commercial work. I have discovered, however, that it is possible to run a heavy duty cap twister at very much higher speeds on similar work. For instance, a speed of 10,000 revolutions per minute on cotton work can readily be attained while producing entirely satisfactory results.

In attempting to run cap twisters of the usual constructions at higher speeds than about 2500 revolutions per minute, a number of difficulties have been encountered, especially in using yarn packages of large diameters. Among these difficulties may be mentioned particularly the excessive ballooning of the twisted strand, the fact that the increased lifting action exerted by the twisted strand on the cap raises the cap off the spindle, and especially the fact that excessive heat is developed both by the friction of the strand, on the cap, and also by the friction between the spindle and the whirl and sleeve that rotate on the spindle. To overcome these objections and to devise a thoroughly satisfactory cap twisting mechanism that will operate at high speeds constitutes the chief object of the present invention.

The nature of the invention will be readily understood from the following description when read in connection with the accompanying drawings, and the novel features

will be particularly pointed out in the appended claims.

In the drawings,

Figure 1 is a perspective view showing one unit of a cap twisting machine constructed in accordance with this invention;

Fig. 2 is a vertical cross sectional view of the unit shown in Fig. 1;

Fig. 3 is a vertical cross sectional view showing a slightly different construction of cap and a different means for controlling the ballooning;

Fig. 4 is a horizontal cross sectional view of a balloon controlling tube embodying a feature of this invention and showing it in its operative relationship to a cap;

Fig. 5 is a front elevation of the tube shown in Fig. 4; and

Fig. 6 is a cross sectional view showing a modified construction of sleeve.

Referring to Fig. 1, the spools or other thread bodies from which the strands or ends are drawn and subsequently twisted together, are indicated at 2, these spools being mounted on suitable pins and the strands being guided around a roll 3 and through suitable thread guides 4 and 5. From the latter point the thread is led to the rapidly rotating spool 6. This spool is supported on a whirl 7 driven by a belt or band 8 in the usual manner, and the whirl has a sleeve 9 extending upwardly therefrom and rigidly secured thereto. The whirl is moved up and down by the usual traverse rail 10, and it is guided during this rotative movement by the stationary spindle 12 which is secured in the spindle rail 14. A cap 15 is mounted on the upper end of the spindle 12.

So far as the general organization and arrangement of these parts is concerned, it is similar to that of the usual cap twisting machines. The strand S of thread is led from the thread guide 5 past the lower edge of the cap 15 to the spool 6, the rapid rotation of this spool serving both to twist the thread and also to wind it on the body of the spool. The gradual raising and lowering movement of the spool imparted to it through the movement of the traverse bar 10 controls the placing of the thread on the spool.

As above stated, the lifting action exerted by the strand on the lower edge of the cap

15 has proved a troublesome factor at high speeds since it raises the cap off the upper end of the spindle. In order to overcome this difficulty, I groove the spindle near its 5 upper end, as shown at 16, Fig. 2, and the cap 15 has a pin 17 driven diagonally therethrough with its end projecting into the bore formed in the top of the spindle cap. This projecting end of the pin enters the groove 16 and positively locks the cap against accidental displacement during the operation 10 of the machine. The direction of the screw thread is such that the rotation of the strand tends to screw the cap on more tightly. 15 Whenever it is desired to remove the cap, however, it is simply necessary to turn the cap in the proper direction to cause the pin 17 to run upwardly in the groove 16. The cap may be replaced again by a reversal of 20 these movements. It is contemplated that this problem may be solved in other ways, as, for instance, by providing the tip of the spindle and the cap with cooperating screw threads, or by providing a bayonet joint connection between them.

The excessive heating of the cap due to the causes above mentioned has proved a serious obstacle to the operation of cap twisting machines at high speeds. I have found, 30 however, that by drilling several holes 18 through the top of the cap, the air currents which are set up by the normal operation of the parts will cool the cap very effectually. That is, air is forced through these apertures 18, partly by the reciprocating movement of the spool 6 within the cap, and partly, also, by the rapid rotation of this spool inside the cap. The natural tendency 40 of the hot air to rise within the cap and pass through the ventilating holes in the top thereof may also account for some of the cooling action produced by this construction. This avoids danger of the cap becoming overheated and it has the advantage of 45 providing an exceedingly economical solution for this problem.

A somewhat different form of cap is shown in Fig. 3, this cap being provided 50 with a knob 21 which forms a convenient handle and facilitates the removal of the cap from the spindle and its replacement thereon.

I have also found that the excessive heating 55 of the sleeve, whirl, and spindle which have been produced in prior constructions when the machines are operated at high speeds, can be overcome by increasing the clearance between the sleeve and the spindle and inserting bearing bushings such as those indicated at 19 and 20, respectively, Fig. 2, 60 between the spindle and the part that rotates on it. It will be observed that these bushings are located near the opposite ends of the sleeve, one preferably being within the whirl 65 7, where it takes the pull of the band, and

being located at the upper end of the sleeve 9. These bushings may be shrunk into the sleeve and may, if desired, be made of brass, bronze or some other material which will reduce the friction created by their contact 70 with the spindle. Since the bearing surface between the spindle and the sleeve is confined to the two points where the bushings 19 and 20 bear on it, it will be less than would be the case if the entire sleeve were 75 in contact with the spindle. A further advantage of this construction is that it facilitates oiling and prevents the sleeve from binding on the spindle due to deflection of the spindle by the lateral pull on the band. 80

Another solution for this problem is shown in Fig. 6 in which the sleeve 9' is contracted or swaged to a reduced diameter at the points 32 and 33. This arrangement 85 confines the bearing between the sleeve and the spindle to the surfaces 32 and 33, and thus reduces the friction.

For the purpose of controlling the ballooning of the thread, I prefer to substantially enclose the cap in a tube. The ordinary balloon controlling or stabilizing ring will not answer the purpose here for the reason that the balloon will form both above and below the ring. A tube, however, such as that shown at 22, Figs. 1, 2, 4 and 5, does 90 effectually control the ballooning. This tube preferably is held in an angular piece 23, Fig. 1, which is supported by brackets 24-24 secured to suitable parts of the machine frame. 100

Figs. 1, 4 and 5 show a self-threading tube which I prefer to use. This tube may be made of a piece of sheet metal rolled into a substantially cylindrical form with one edge overlapping the other, and the inner wall at the overlapping portion has a V-shaped notch 25 cut therein, as best shown in Fig. 5. The outer wall terminates slightly beyond this notch and has a corresponding V-shaped contour, as indicated 110 at 26, the tip or apex of this V preferably being turned back, as shown at 27, to facilitate the introduction of the thread. Within the tube a V-shaped piece 28, complementary to the notch 25, as best shown in Fig. 5, is 115 sweated to the tube and is gradually reduced in thickness as it extends away from the edge 25. This construction provides a tube with a smooth interior of substantially uniform internal diameter. It avoids the use 120 of a stepped construction which would produce a slapping or pounding action where the rapidly rotating thread passed over such a step or irregularity. The V-shaped cut in the tube also avoids the presence of any opening through which the strand might fly, or in which it might catch and be broken. It will be noted that the direction 125 of rotation of the strand is counter-clockwise with reference to Fig. 4, so that the 130

strand travels from the apex of the V-shaped cut toward the base or widened part of this cut.

In the arrangement shown in Fig. 3, two balloon controlling rings 30 and 31 are used instead of a tube, these rings being located at suitable distances apart to control the ballooning at all times. This arrangement is satisfactory under certain conditions.

10 I have demonstrated by actual practice that a cap twisting mechanism of the character above described is entirely successful in operation at speeds heretofore regarded as impractical. Furthermore, the machine performs the twisting operation on cotton thread at the high speeds above mentioned fully as satisfactorily as it is performed at very much lower speeds with the usual ring twister.

20 While I have herein shown and described the best embodiment of my invention which I have so far devised, it will be appreciated that the invention is not limited to embodiment in the precise form shown. It is also 25 contemplated that some of the features of this invention will be useful in the twisting of other yarns.

Having thus described my invention, what I claim as new is:

30 1. In a cap twisting mechanism, the combination of a stationary spindle, and a cap

detachably mounted on said spindle but locked against accidental disengagement from the spindle.

2. In a cap twisting mechanism, the combination of a stationary spindle, a cap mounted on said spindle, and a connection between said cap and spindle preventing the cap from moving axially off the spindle but enabling it to be removed from the 35 spindle by a turning movement relatively to said spindle.

3. In a cap twisting mechanism, the combination of a stationary spindle, a cap mounted on said spindle, said spindle having a spiral groove formed therein near its upper end, and said cap having a pin 40 projecting into the bore thereof to enter said groove and serving to lock the cap on said spindle. 45

4. In a cap twisting mechanism, the combination of a stationary spindle, a whirl mounted for rotation on said spindle and for up and down movement thereon, said whirl being adapted to support a thread body, a cap mounted on the upper end of said spindle, said cap having holes through the top thereof to permit a circulation of air 50 through said cap for ventilating and cooling it, and means for controlling the ballooning 55 of a thread running to said thread body. 60

SERGE DANILOFF.
